UNITED STATES PATENT OFFICE.

AMBROSIUS BRIECHLE, OF BROOKLYN, NEW YORK, ASSIGNOR TO WALES ADDING MACHINE COMPANY, OF WILKES-BARRE, PENNSYLVANIA, A CORPORATION OF PENNSYLVANIA.

CALCULATING-MACHINE.

1,368,424.

Specification of Letters Patent.

Patented Feb. 15, 1921.

Application filed April 21, 1919. Serial No. 291,459.

To all whom it may concern:

Be it known that I, AMBROSIUS BRIECHLE, a citizen of the United States, residing in the borough of Brooklyn, city and State 5 of New York, have invented new and useful Improvements in Calculating-Machines, of which the following is a specification.

This invention is especially directed to 10 vibrating or shuttling mechanisms for paper carriages, which shift the carriage automatically in opposite directions alternately, on successive operations of the driving means, to enable entries to be made in two columns successively and alternately.

15 The invention is further directed to those mechanisms which coöperate with a shuttle carriage whereby to extend the usefulness of a machine of this nature, and enable it to perform methods of compilation more 20 readily than heretofore, due to the particular and novel arrangement or relationship of the functional mechanisms.

Thus, the application of a shuttling mechanism alone to the usual shiftable paper 25 carriage of a single counter calculating machine, results in shifting the carriage back and forth between two columns, but the amounts printed in each column, would be collectively accumulated on the single set 30 of counters, and the successive amounts would be printed in staggered relation in the two columns, due to the operation of the line spacing mechanism synchronously with each operation of the machine.

35 While such a machine may have its uses, it is desirable to provide means to eliminate the action of the line space mechanism when the shuttle carriage is positioned to enable amounts to be printed in one of the columns, 40 to permit the imprint of two related amounts on the same line, although located in separate columns.

Furthermore, in many lines of work, it is 45 desirable to prevent the accumulation of the amounts printed in one of the columns, as when listing car numbers and weights, check numbers and amounts, or the like, by rendering the accumulating mechanism inoperative when the carriage is positioned to bring 50 the column for the identifying or designating numbers, to the printing point.

One object of my invention is to improve and simplify, as well as strengthen, devices to accomplish the above mentioned results,

to render the machine more durable, as well 55 as to compactly arrange the parts, to avoid injury thereto, and to reduce the liability of getting out of order.

To these ends, I provide an alternating mechanism of strong and durable construction, arranged parallel to and adjacent the base of the machine where it does not interfere with other moving parts. This alternating mechanism is connected to the carriage to reciprocate the latter between two 65 columns.

In the present instance, I have shown the alternating mechanism as being actuated from the usual main drive shaft, but it will be understood that some other suitable 70 source of power may be employed. The means to disable the line space mechanism, and to prevent the addition of amounts is of simple and efficient character, which automatically operates independently of the 75 carriage, and as an incident to the operation of the alternating mechanism.

A further object of my invention is to relieve the operator of the necessity, heretofore present, of devoting special attention 80 or thought to the adjustment of the line space disabling mechanism, to which end, I place the line space disabling mechanism under control of the adjustable connection between the alternating mechanism and the 85 carriage, which connection is set by the operator to effective or ineffective position. The line space disabling mechanism is placed in condition for action as an incident to effecting such connection, and is disabled, as an incident to the interruption of 90 such connection.

Still another object is to provide a most simple and effective setting means to control the operation of the alternating mechanism, so arranged that, without disabling or interrupting the connection between the alternating mechanism and the carriage, the shuttling of the latter and the elimination of the line spacing operation is readily 100 avoided by operating the setting means to retain the alternating mechanism in idle position.

This object is the more easily attained in the present instance, because there is no 105 positive connection between the driving means and the alternating mechanism.

A still further object of the invention is

to positively lock the carriage in either of its adjustable positions when operated by the alternating mechanism, against rebound in one direction, or overthrow in the opposite direction.

Another object is to enable the operator to control the automatic non-adding mechanism from the usual non-add key, thereby simplifying the construction and reducing the number of parts.

The above and other objects and advantages will be more fully set forth herein-after and particularly pointed out in the claims.

15 In the accompanying drawings, illustrating one embodiment of my invention, Figure 1 is a view in side elevation, of the well-known Wales calculating machine, equipped with one form of my invention, 20 the parts being at rest in their home positions;

Fig. 2 is a longitudinal sectional view through the machine, parts being omitted;

25 Fig. 3 is a detail sectional plan view of a portion of the machine, showing the alternating mechanism;

Fig. 4 is a detail view in side elevation of the means to lock the carriage at either end of its travel;

30 Fig. 5 is a detail view of the disabling means for the alternating mechanism;

Fig. 6 is a fragmentary detail view, looking rearwardly, illustrating the connection between the alternating mechanism and the 35 carriage, and the line spaced disabling mechanism, the latter being in effective position;

Fig. 7 is a detail end view of the carriage, showing the effective position of the 40 line space disabling mechanism;

Fig. 8 is a detail rear view, showing the 45 positions occupied by the parts when the carriage is at the opposite end of its travel to that shown in Fig. 6, the line space disabling mechanism being ineffective, and

Fig. 9 is a vertical cross sectional view through the carriage, showing the means to 50 interrupt the transmission of power from the alternating mechanism to the carriage.

Calculating machines of the Wales type are shown in U. S. patents to Wales, 797,032, August 15, 1905; McFarland, 842, 55 232, January 29, 1907; and 880,159, February 25, 1908; White, 940,766, November 23, 1909; and McFarland, 1,024,013, April 23, 1912, to which reference is directed for a more complete description.

Suffice it to say that a base 968 (Figs. 1 and 2) supports parallel side frames 967, 60 (Figs. 1 and 3) between which are arranged, from front to rear, a keyboard section, an accumulating mechanism, and a printing mechanism.

The keys 117 (Fig. 2) of the keyboard,

arranged in denominational rows, operate 65 levers 116, to control similarly arranged stops 115. Depression of any of the keys 117 in a denomination, projects the corresponding stop 115 into the path of its co-acting rack 310, and a latch 114 maintains 70 the stop where adjusted. The racks 310 are each pivotally mounted on their individual front and rear supporting arms 312 and 311, respectively, there being as many racks as there are denominational rows of stops. 75 The front supporting arms 312 of the several denominational racks, are journaled on a cross shaft 300 having its bearings in the side frames 967 and the several rear supporting arms 311 are journaled on a cross 80 rod 301 mounted in the side frames.

A restraining and restoring rod 205, carried by a series of parallel fingers 265^m projecting from a rotatably supported cross bar 265, normally lies in front of and in 85 contact with the front supporting arms 312, to hold the racks 310 in their retired or home positions against the tension of their individual drive springs 383, which springs are connected at their opposite ends to the 90 rear supporting arms 311 and to the restraining and restoring rod 205, respectively.

A main drive shaft 200 journaled in the side frames 967, carries an arm 210 fixed 95 thereto, and a wiper 256 on the arm 210 projects into and traverses a cam slot 220^m in a crank 220 secured to the cross bar 265.

A main restoring spring 285 connected with the main drive shaft, normally holds 100 the latter in its home position and through the arm 210, wiper 256 and crank 220, maintains the restraining and restoring rod 205 against the front arms 312 to prevent the advance thereof.

105 Turning the main drive shaft 200 forwardly, as by means of a handle 210^d, against the tension of the restoring spring 285, causes the wiper 256 to traverse the cam slot 220^m to rock the crank 220 and 110 cross bar 265, and withdraw the restraining and restoring rod 205 from in front of the front supporting arms 312, thereby further tensioning drive springs 383, and freeing the supporting arms for advancement.

115 The arms 311, 312 rock forwardly under the tension of their drive springs as the restraining and restoring bar is withdrawn, advancing the racks 310, until the forward ends of the racks contact the projected 120 stops 115, or the rack detents 221 in those denominations wherein no stops have been projected. The stops, when projected, displace their denominational rack detents 221 which normally lie in the paths of the racks, 125 and are journaled at their forward ends on a cross shaft 202.

The main drive shaft is released at the

end of its forward stroke, to the action of the restoring spring 285, which reverses the direction of rotation of the shaft to return the parts to their positions of rest, and during such return stroke, means (not shown, but common to the Wales machine) rocks a cross shaft 201 to press trip members 252 carried thereby, against the projecting ears 114^m of the latches 114, to cause them to release the stops 115 for restoration to idle position.

Levers 322 (Fig. 1) pivoted at 952^a to the outer faces of the side frames 967, support the opposite ends of a counter axle 400 extending across the racks 310 (Fig. 2). Counters 490, each having a pinion 435 associated to turn therewith, and journaled for independent rotation on the axle, are adapted to engage and disengage the racks 310.

Mechanism to effect these results, includes counter-disengaging props 319 (Fig. 1) pivoted at their upper ends to the levers 322, and slotted at their lower ends to embrace and rest upon the ends of a horizontally extending trip rod 303 (Figs. 1 and 2) carried in radius bars 323 (Fig. 2) journaled on the cross shaft 300. The radius bars and trip rod thus form a swinging frame. Links 214 connected at their rear ends to the trip rod 303, extend forwardly to cranks 210^m, 212 on the main drive shaft 200. The trip rod 303 swings in an arc about the shaft 300 as a center, and the main drive shaft, when in its home position, retains the trip rod at the upper rear end of its path of travel, wherein the props 319 support the levers 322 and the axle 400 in their raised positions, to hold the counters 490 and pinions 435 out of engagement with the racks 310.

The trip rod 303, because of its positive connection with the drive shaft 200, advances in a descending arc on the forward stroke of the main drive shaft, and withdraws its support from the props 319, levers 322 and axle 400. This would operate to lower the counters 490 into engagement with the racks 310 at the outset of the forward stroke of the main drive shaft prior to the advance of the racks 310, and to postpone such action in an adding operation, legs 316 (Fig. 1) depending from the opposite ends of the counter axle 400, are equipped at their lower ends with feet 316^m to contact steps 958^a projecting from the adjacent side frames 967, just as the trip rod 303 starts its descent, and thus continue to maintain the counters out of mesh with their racks.

The trip rod 303 continues its travel along a descending forward arc, and idly traverses the slots in the lower ends of the props 319, and a second set of slots formed in the for-

ward ends of bridle links 321, the rear ends 65 of which are connected to the legs 316, to afford time for the advance of the drive racks 310, as heretofore explained.

As the trip rod approaches the forward end of its travel, it contacts the outer end 70 walls of the slots in the bridle links 321 to trip the legs 316, thus depriving the counters 490 of support, and the counters or their pinions 435, drop into mesh with the racks 310 after the latter have completed 75 their advance, and substantially at the same time that the main drive shaft 200 completes its forward stroke.

The main drive shaft, during its return stroke, causes the arm 210 to retrace its path 80 along the cam slot 220^m to force the restraining and restoring rod 205 against the advanced supporting arms 312 to retire the racks to their normal positions, and the racks, during such retirement, turn the 85 counters 490 engaged therewith, to register thereon an amount corresponding to the values of the denominational keys depressed.

Meanwhile, the trip rod 303 is idly retracing its path along a rearwardly inclined arc, until, near the end of the return stroke of the main drive shaft, and after the racks 310 have completed their operation of the counters, the trip rod contacts the upper end 95 walls of the slots in the disengaging props 319 to lift the latter with the levers 322 and counter axle 400, to thereby disconnect the counters 490 from the retired racks 310. The legs 316 ascend with the counter axle 100 400 until their feet 316^m clear the steps 958^a, whereupon springs 385^b (Fig. 1) snap the legs and feet into alinement with the steps.

To provide means whereby to list the various amounts set up on the keyboard, as 105 well as to print totals and sub-totals accumulated on the counters 490, the rear supporting arms 311 (Fig. 2) have rearward extensions 311^m which swing up and down, as the supporting arms rock forwardly and 110 backwardly. Links 515 connect the respective extensions 311^m with individual type carriers 514, a vertical row of types 561 corresponding to the related row of keys 117, being supported in the head of each 115 type carrier. The intervals between the key-set stops 115 bear a predetermined relation to the intervals between the centers of the successive types 561 so that the arrest of the racks 310 on their advance, positions the 120 proper types at the printing line.

Individual latches 511 journaled on a cross rod 504, normally lock the printing hammers 510, journaled on a cross shaft 500, in set or retracted position. Trip bars 513 125 under the influence of springs 583, and controlled by the rear extensions 311^m, ascend with the rear extensions to release the cor-

- responding individual hammer latches 511. A universal latch 518 fixed on a shaft 502, continues to retain the released hammers retracted until the extensions 311^m have completed their positioning strokes to locate the proper types 561 at the printing line, after which the universal latch 518 is lifted by the usual Wales means (not shown), to release the hammers 510 to the action of their tensioned drive springs 580. The hammers strike firing pins 562^b and drive the latter against the positioned types to effect the imprint thereof on the paper held by a platen 2094.
- Means (not shown) controlled by the main drive shaft 200, operates during the return stroke of the main drive shaft 200 to re-cock the hammers 510, the universal latch 518 returns to effective position, the racks 310 upon their retirement, lower the extensions 311^m with their type carriers 514, and the trip bars 513, the latter freeing the individual hammer latches 511 for effective operation.
- Carriageways 2067^m extending across and connecting the rear ends of the side frames 967 to which they are secured, accommodate between them, a carriage slide 2065 (Figs. 2, 6, 8 and 9) adapted to travel back and forth.
- Braces 2067 connect the ways to afford strength and rigidity thereto.
- A shaft 2004 journaled in end plates 2010 fastened to the carriage slide 2065, supports the platen 2094 for rotation.
- Line spacing mechanism to turn the platen, includes a reciprocatory thrust bar 2026, (Fig. 1), the forward end of which is connected to a brace rod 302 connecting the radius bars 323, and forming a part of the swinging frame which the main drive shaft oscillates. The rear end of the thrust bar 2026 terminates in a foot 2026^m which, when the thrust bar is at the rear end of its travel, as in Fig. 1, contacts a transversely extending line space bail comprising a rod 2002 supported in arms 2016^a having trunnions 2053 (best shown in Fig. 8) journaled in the respective end plates 2010 of the carriage. A feed spring 2486 (Fig. 8) presses the universal line space rod toward the foot 2026^m. An operating bell crank 2016 (Fig. 2) fast on one of the trunnions 2053, pivotally supports at 2033^a, an upwardly projecting line space pawl 2014, adapted to engage and turn a ratchet 2020 fixed to the platen shaft 2004. The thrust bar 2026, by retaining the universal line space rod 2002 in its retracted or rearward position, holds the line space pawl 2014 out of contact with its ratchet 2020 to enable the platen to be manually turned in either direction.

The main drive shaft, on its forward stroke, draws the swinging frame 323, 303 forwardly, and with it the brace rod 302, to

withdraw the thrust bar 2026 relatively to 65 the universal line space rod 2002. The feed spring 2486 causes the rod to follow the thrust bar, thereby swinging the supporting arms 2016^a forwardly and rocking the operating bell crank 2016 and line space pawl 70 2014 to draw the tooth of the pawl idly over the ratchet preparatory to taking a bite thereon.

The swinging frame restores during the return stroke of the main drive shaft, and 75 forces the rear end of the thrust bar 2026 against the advanced line space rod 2002 to rock the latter back to its home position against the tension of the feed spring 2486. The line space rod, as it swings rearwardly, 80 engages the line space pawl 2014 with the ratchet 2020 and turns the latter and the platen to feed the paper in line spacing direction.

The carriage is longitudinally adjustable 85 in column spacing direction across the machine, to bring one or another of the columns to the printing point. Such adjustment or cross tabulating feed may be accomplished manually or automatically. Tabulating 90 stops 2018^b (Fig. 2) adjustably secured to a toothed tabulating bar 2092^b, each carry a stop projection 2018^m adapted to contact an abutment 2091^a fast on one of the carriage rails 2067^m, to hold the carriage in any of its 95 adjusted positions. Trunnions 2056 (Fig. 8) and 2093^b (Fig. 1) respectively, secured to the opposite ends of the tabulating bar 2092^b, turn in the end plates 2010 of the carriage, the trunnion 2056 projecting 100 through its end plate and carrying a release lever 2022^d (best shown in Fig. 2) to enable the operator to rock the tabulating bar against the tension of a spring 481^a. (Fig. 8) to withdraw the active stop 2018^b from engagement with the abutment 2091^a, and slide the carriage in either direction to bring any selected column to the printing point opposite the type carriers 514. A slot 2022^m (Fig. 2) in the release lever 2022^d embraces 110 the platen shaft 2004 to limit the throw of the release lever in either direction. The spring 481^a restores the tabulating bar with its stops to effective position upon the removal of pressure from the lever 2022^d 115

To print the accumulated amount on the counters and clear the latter, the operator depresses a total key 327 (Fig. 1). A latch 326^f releasably connects the total key with the forwardly extending arm of an angular set lever 317^b fast on the left hand end of the cross shaft 300, a somewhat similar lever, not shown, being fastened to the right hand end of the shaft. Links 315 connect the upper arms of the respective set levers with the corresponding detaining legs 316. Depressing the total key 327 rocks the set levers 317^b to draw the links 315 forwardly and dis-

place the legs 316 relatively to their steps 958^a.

The set lever 317^b carries a keeper stud 354, which, when the set lever is rocked 5 downwardly, displaces a dog 216^d pivoted to a quadrant 211 fast on the main drive shaft 200 and turning therewith. The keeper stud passes beneath the tooth of the dog 216^d which thereupon restores to normal position to retain the set levers where 10 adjusted, against the tension of a restoring spring 382.

The upwardly extending arm of one of the set levers 317^b, has a loose connection 359 15 with a slide 320 having an inclined slot 320^m to accommodate a projection 251 on a crank 222^d fast on the protruding end of the cross shaft 202 on which the rack detents 221 are journaled. Similar cranks 222^m (Fig. 2) 20 fast on the shaft adjacent the inner faces of the side frames 967, support a cross rod 204 extending beneath the series of rack detents 221. The set lever 317^b, when rocked by the key 327, advances the slide 320 to cause the 25 projection 251 to ride up the inclined slot 320^m and rock the shaft 202 to press the cross rod 204 against the rack detents 221 and raise the latter out of the paths of their corresponding racks 310.

30 The main drive shaft, as usual, at the outset of its forward stroke, swings the trip bar 303 downwardly and forwardly, and the detaining legs 316 being displaced, the counters 490 drop into mesh with their racks 35 prior to the advance of the latter.

The main drive shaft also withdraws the restraining and restoring bar 205 from in front of the supporting arms 312, and tensions the drive springs 383, which advance 40 the racks 310, owing to the displacement of the rack detents 221. The racks turn the counters in a direction reverse to that in which they turn when accumulating amounts, until the counters are arrested in 45 their zero positions in a manner common to the Wales machine and not herein shown.

The advance of the racks 310 positions, at the printing line, those types 561 which correspond to the digits registered on the respective counters, after which the printing mechanism is released to impress such types 50 on the paper.

The quadrant 211 turns with the main drive shaft and interposes an arcuate rib 217 (Fig. 1) over the keeper stud 354 to maintain the set levers where adjusted during the forward stroke of the main drive shaft.

If the counters are to remain in their zero 60 positions, it is necessary to disconnect them from the racks prior to the retirement thereof, on the return stroke of the main drive shaft, to effect which, the upwardly extending arms of each of the set levers 317^b (Fig. 1) carry thrust studs 355 (Fig. 1) adapted,

when the set levers are rocked by the depression of the total key 327, to clear, and lie in front of, shoulders 314^m formed on the forward ends of thrust links 314, whose rear ends are connected to the upwardly extending arms of lifting bell cranks 313 journaled on the outer ends of the cross shaft 301. The remaining arms of the lifting bell cranks extend forwardly behind the legs 316 to lie adjacent inwardly projecting studs 357^d on the legs. 75

As the main drive shaft completes its forward stroke, the inclined rear end of the arcuate rib 217 on the quadrant clears the keeper stud 354 on the set lever 317^b, whereupon the spring 382 operates to partially restore the set levers to their normal positions. The thrust studs 355 on the upper arms of the set levers contact the shoulders 314^m on the thrust links 314 to rock the lifting bell cranks 313 rearwardly and bring their forwardly extending arms against the lifting studs 357^d on the legs 316. The restoring spring 382, however, is too weak to overcome the weight of the counters 490 and connected parts, and hence the keeper stud 354 90 remains in the path of return of the inclined rear end of the locking rib 217.

The main drive shaft, at the beginning of its return stroke, presses such inclined rear end of the locking rib 217 against the keeper 95 stud 354 to force the latter upwardly to normal position, together with the set levers 317^b, which, in turn, force the thrust links 314 farther rearwardly to rock the lifting bell cranks 313. The bell cranks raise the 100 legs 316 to disengage the counters 490 from their drive racks 310, after which the racks and type carriers 514 retire idly to their positions of rest, and the trip rod 303 swings the counter-disengaging props 319 back to normal effective position. Release studs 361 on the props displace the thrust links 314, as the props return to enable the lifting bell cranks 313 to restore to idle position. 105

In case the operator desires to print the 110 amount accumulated on the counters, and retain the amount on the counters for further additions thereto, it is only necessary to hold the set levers 317^b against release at the end of the forward stroke and until the 115 main drive shaft on its return stroke, restores the arcuate rib 217 to position over the keeper stud 354.

This is accomplished in the present instance, by depressing a sub-total key 327^b 120 (Fig. 1) having a foot 327^m overlying the forwardly extending arm of the set lever 317^b, to rock the arm downwardly, as in totaling, a lock (not shown) operating to maintain the sub-total key depressed until 125 near the end of the return stroke of the main drive shaft. By retaining the set levers 317^b where adjusted, during the return

stroke of the main drive shaft, the thrust studs 355, thrust links 314, and lifting bell cranks 313 remain idle, thereby permitting the counters 490 to remain engaged with the 5 racks 310, which, on the return stroke, operate, as in adding operations, to again register the total amount on the counters.

In such sub-totaling operation, the counters are disengaged from their racks at the 10 end of the return stroke, in the same manner as in adding operations.

Many details of construction and operation have been omitted from the foregoing explanation, information regarding which 15 may be found in the patents heretofore mentioned, the various devices hitherto set forth constituting a part of my invention only in so far as they are combined with the novel features now to be disclosed.

20 It will be remembered that the swinging frame, including the radius bars 323, trip rod 303 and brace rod 302, oscillates forwardly and backwardly synchronously with the forward and return strokes of the main 25 drive shaft 200, which shaft positively operates the frame through the link connections 214, and cranks 210^m, 212.

To mechanically effect the reciprocation of the paper carriage between two columns 30 successively and alternately, I conveniently utilize the swinging frame as a driving or actuating medium, to which end, I apply depending actuating arms 1, 1' to the frame, the arms constituting extensions of the 35 radius bars 323, to sweep forwardly and backwardly in planes parallel with and adjacent to the side frames 967. The trip rod 303 passes through the actuating arms 1, 1' intermediate their ends, (Figs. 2 and 4), the 40 upper ends of the arms being slotted to fit about the cross brace 302.

An alternating member or rocking beam 2 (Figs. 2 and 3) lies in a plane parallel with and across the base 968, the member being pivoted at 3 (Fig. 3) intermediate its 45 ends to a pedestal 968^p (Fig. 2) projecting upwardly from the base. The pivot terminates in a cap 4 (Fig. 3) overlying the rocking beam 2 to maintain it in a horizontal 50 plane, and prevent its tilting, as it rocks from one to the other end of its path.

Substantially triangularly-shaped tappets 5, 5' are pivotally secured at 6 and 7, respectively, to the opposite ends of the beam 55 or alternating member 2, the pivots being located approximately centrally of the tappets. A bar 8 extending between and pivotally connected to the rear ends of the tappets 5, 5' at points eccentric to the pivots 6 and 7, operates to transmit movement from 60 either tappet to the other, to enable them to turn simultaneously in clockwise or counter-clockwise direction on their respective pivots 6 and 7, until the forward face 5^m of one 65 or the other of the tappets 5, 5' strikes its

coacting stop 9 on the rocking beam to arrest the tappet. Arrest of either tappet operates through the connecting bar 8 to arrest the other tappet.

It will be noted that the opposed tappets 70 assume an alternately effective relation, that is, when one of the tappets (as the tappet 5' in Fig. 3) has been arrested by its stop 9 at one limit of its clockwise travel, at which its outer free end forms a prolongation of 75 the adjacent end of the rocking beam 2, extending into the path of its corresponding actuating arm 1', the opposite tappet 5 has been swung forwardly in clockwise direction from a similar effective position (see 80 dotted lines, Fig. 3) to its retracted or idle position, shown in full lines in Fig. 3, with its outer free end or finger withdrawn from the path of its actuating arm 1.

With the tappets 5, 5' in this adjustment, 85 the actuating arm 1 will swing idly forward and back, clearing the adjacent end of the rocking beam 2. It will be noted that there is no positive or direct connection between the actuating arms 1, 1' and the alternating 90 mechanism, and also that the planes of travel of the actuating arms are at right angles to the plane of operation of the alternating member.

I have contrived to automatically adjust 95 the tappets separately and alternately from and to their effective positions, by means controlled by the alternating member 2, itself. Thus, a switch lever 10 is preferably pivoted intermediate its ends at a point 11, 100 (Fig. 3) on the pedestal 968^p behind the pivot 3 of the alternating member. The pivot 11 divides the switch lever 10 into long and short arms, the shorter arm being in turn pivoted to the alternating member 2 by 105 a slot and pin connection 12 between and in line with the pivotal supports 3 and 10 of the alternating member and switch lever, respectively, when the rocking beam 2 lies intermediate the ends of its stroke, at which 110 time the switch lever 10 lies at substantially right angles to the rocking beam.

It will thus be seen that the radii 3, 12, and 11, constitute a toggle, and that the passage of the pivotal connection 12 from one limit of its path to the other across the dead center between the pivotal points 3, 12, 11, operates to switch the longer arm of the lever 10 from side to side. Hence, looking from the front of the machine, if the left hand branch of the rocking beam 2 swings rearwardly in clockwise direction, it will throw the shorter arm of the switch lever 10 toward the right and swing the longer arm of the lever toward the left, and vice versa. Divergent springs or flexible links 13, 14 (Figs. 2 and 3) connect the longer arm of the switch lever 10 with the connecting bar 8 on opposite sides of its center. The springs 13, 14 may be conveniently 130

connected to posts 15 depending from ears 16 formed at opposite ends of the tappet bar 8, the ears 16 affording clearance for the posts 15, relatively to the rocking beam, 5 to insure uninterrupted travel of the tappets 5, 5' to effective position.

The extent of throw of the rocking beam 2 in either direction is determined by the 10 arc of travel of the actuating arms 1, 1', which in their home positions, lie at the rear ends of their strokes, (Figs. 1, 2 and 3) and as one or the other of the tappets 5, 5' is 15 always in the path of its correlated actuating arm, the rocking beam or alternating member 2 is held at one or the other of its extreme positions, when the machine is at rest.

Assuming the parts to be in the positions shown in full lines in Fig. 3, it will be seen 20 that the actuating arm 1' is in contact with the effective tappet 5', having rocked the alternating member 2 in a clockwise direction to one of its extreme positions. The alternating member, in turn, has swung the 25 longer arm of the switch lever 10 in a counter-clockwise direction to relax the tension on the flexible link or spring 13 and increase the tension of the opposing flexible link or spring 14 to render the latter superior to 30 the former.

The temporarily superior spring 14, tends to shift the connecting bar 8 to the left (looking from the front of the machine) to rock the idle tappet 5 counter-clockwise to 35 effective position, and simultaneously, rock the effective tappet 5' in the same direction to idle position, but is prevented from so doing by the pressure of the actuating arm 1' against the effective tappet 5'.

40 The main restoring spring 285 maintains the parts in these positions until the next forward stroke of the main drive shaft, whereupon the actuating arms 1, 1', as they advance, draw away from the tappets 5, 5' 45 to free the latter to the action of the superiorly tensioned spring 14. This spring then swings the tappet 5 counter-clockwise until its inner face 5^m strikes the adjacent stop 9, at which time the tappet lies in the path 50 of return of its actuating arm 1, (see dotted lines in Fig. 3), and simultaneously rocks the formerly effective tappet 5' in a similar direction, to idle position.

55 The stop 9, by arresting the tappet 5, operates through the connecting bar 8 to arrest the tappet 5' in its idle position against further rotation under the influence of the spring 14.

60 The rocking beam 2 remains where adjusted by the actuating arm 1', with its right hand end advanced beyond the left hand end, so that the newly positioned right hand tappet 5 intercepts its actuating arm 1, shortly after the main drive shaft 200

starts on its return stroke. The actuating 65 arm 1 then rocks the alternating member 2 in a counter-clockwise direction, thereby advancing the left hand end of the alternating member. The latter, in turn, swings the longer arm of the switch lever 10 in a clockwise direction to tension the spring link 13 and relax the spring link 14. The mechanism is thus set to shift the tappets 5, 5' to 70 their respectively opposite positions during the withdrawal of the actuating arms 1, 1' 75 on the next forward stroke of the main drive shaft, whereupon the operation above described is repeated, except that the tappet 5' again becomes effective to enable the actuating arm 1' to return the alternating 80 member to the full line position shown in Fig. 3, and the tappet 5 shifts to idle position.

Obviously, the actuating arms 1, 1' on successive complete operations of the main 85 drive shaft, will rock the alternating member in first one direction and then the other alternately.

A tail 2^m extends rearwardly from the alternating member 2 to a point beyond the 90 rear end of the base 968, where it is conveniently connected to the carriage-shifting mechanism. A depending fork 17 pivoted to the outer end of the tail 2^m, loosely embraces a wrist pin 18 projecting from a 95 crank 19 forming part of a communicating lever 19, 20. The upper end of the crank 19 is secured to the inner end of a hub 21 journaled on a pintle 22 extending rearwardly from a hanger 23 suspended 100 from the lower rail 2067^m of the carriage. A cross head 24, fast on the outer end of the hub 21, carries at one end a pair of laterally projecting apertured lugs 25, the lugs being spaced apart from each other to 105 embrace a similar pair of lugs 26 projecting from the lower end of the upper crank 20 of the communicating lever 19, 20. A hinge pin 27 connects the pairs of lugs, this construction enabling a movement of the upper 110 crank 20 of the communicating lever relatively to the lower crank 19, (see dotted lines Fig. 9) in an arc at an angle to the oscillatory travel of the crank 19. A stop flange 20^m on the crank 20 contacts the 115 cross head 24 to limit the travel of the crank 20 relatively to the crank 19, in one direction.

A separable coupling 28, 29 releasably connects the crank 20 with a bar 30 mounted in brackets 31 depending from and traveling with the carriage slide 2065. In the present instance, I have found it convenient to journal one member of the coupling, as the female member 28, in the upper end of the crank 20 the inner end of the female member being slotted, as at 32, (Fig. 3) and the outer end carrying a finger piece 33,

whereby to turn the coupling member 28 to cause the slot 32 to slidably fit over a rib 34 formed on the male member 29 of the coupling. The male member of the coupling embraces, and is adjustable along the bar 30, a set screw 35 or other convenient means, operating to retain the male member 29 where adjusted along the bar 30.

To retain the coupling members connected, I provide the cross head 24 with a rearwardly projecting post 36 supporting at its outer end, a turn button 37 adapted to pass through a slot 38 (Fig. 8) in the adjustable crank 20, when the latter is swung 10 on its hinge 27 to engage the male and female members of the coupling 28, 29, after which the button is turned to effective position transversely of the slot, and retains the adjustable crank in position to communicate 15 movement to the carriage.

A spring 39 encircling an operating rod or finger 40 arranged parallel with the pindle 22 and having bearings in the crank 19 and cross head 24 of the communicating lever, is confined between the outer face of the crank 19 and a set collar 41 on the rod, and presses the outer end of the rod against the adjustable crank 20 of the lever 19, 20 to disengage the coupling members 28 and 29.

From the foregoing, it will be noted that the tail 2^m of the alternating member 2, will shift from side to side in a horizontal plane on successive operations of the actuating arms 1, 1'. The tail will oscillate the lever 19, 20, in a vertical plane, and the lever will communicate motion to the carriage to drive the latter back and forth alternately on successive operations of the actuating arms. The fork 17 turns in the tail 2^m as the latter 35 shifts back and forth, to prevent binding between the fork and the wrist pin 18, and the slot in the fork is sufficiently long to accommodate the arcuate travel of the pin and still maintain engagement therewith. Likewise, the female member 28 of the separable coupling 28, 29 turns in the adjustable crank 20, and slides up and down on the rib 34, as the crank 20 rocks back and forth, to permit the conversion of the oscillating motion 40 of the lever 19, 20 into the reciprocating motion imparted to the paper carriage, without cramping.

To prevent any possible hindrance to the shuttling operation of the carriage in either direction, due to the engagement of any of the tabulating stops 2018^b with the abutment 2091^a, I arrange means to hold the tabulating mechanism inactive when the carriage is to be automatically reciprocated. 55 To this end, the manually-operable disabling lever 2022^d carries a spring-pressed pin 42 (Fig. 8) axially slidable in a sleeve 43 carried by and projecting through the disabling lever. The inner end of the locking pin 60 removably enters a hole 44 in the

adjacent end plate 2010 of the paper carriage.

A head 45 on the outer end of the pin 42 carries a key 46 adapted to seat in a notch 47 formed in the outer end of the sleeve. 70

Normally the pin 42 is withdrawn and slightly rotated to unseat the key 46 and cause it to rest against the outer unnotched portion of the outer end of the sleeve 43 to retain the pin 42 in idle position and enable 75 the spring 481^a to return the tabulating bar 2092^b and stops 2018^b to, and hold them in, effective position.

But when it is desired to lock the tabulating mechanism in idle position, the pin 42 is 80 turned until its key 46 registers with the notch 47, after which the disabling lever 2022 is rocked to shift the tabulating mechanism to idle position. The disabling lever 2022, during such operation, brings the pin 42 into registry with the hole 44 in the end plate 2010, into which hole the pin snaps to lock the parts where adjusted.

In case the operator forgets to adjust the tabulating mechanism to ineffective position prior to shuttling the carriage, the stop 2018^b in engagement with the abutment 2091^a will restrain the carriage against operation, and interrupt the operation of the machine, but no damage or injury will be 90 effected, as such restraint merely prevents the return of the main drive shaft under the influence of the main spring 285, and as soon as the tabulating stop 2018^b is disengaged from its abutment 2091^a, the shuttling 100 mechanism will complete its operation.

To insure the accurate positioning of the carriage at each end of its shuttling stroke, irrespective of the speed or violence with which the machine is operated, I provide 105 automatically operable means to positively arrest the carriage upon its arrival at either end of its travel.

As one means to effect this result, I arrange a substantially vertical strut 48, 110 (Figs. 2, 3 and 4) through the upper end of which passes a cross rod 508^d extending between the side frames, the lower end of the strut being conveniently anchored at 49 to the base 968. A hasp 50 pivotally connected at 51 to the strut extends forwardly and carries a lateral flange 50^m adapted to overlie and rest upon a keeper formed by an upward extension of the pivot 7 of the adjacent tappet 5'. A spring 52 presses the 115 hasp down upon the keeper. The flange 50^m is provided with locking apertures 53 (Fig. 3) located a distance apart equal to the arcuate travel of the pivot 7, to enable the hasp to snap over the keeper when the latter reaches one or the other end of its travel. Preferably the extended end of the pivot 7 is reduced in diameter to enter guide slots 53^m which communicate with their respective apertures 53, and are entered by the 120 125 130

keeper just prior to its arrival at the end of its stroke, to position the apertures to register with the keeper.

By locking the alternating member 2 in either of its adjusted positions, the hasp prevents overthrow or rebound of the carriage, which is positively connected with the alternating member through the communicating lever 19, 20.

10 I arrange to automatically disengage the hasp 50 and the keeper 7 prior to the actuation of the alternating member 2 on which the keeper is mounted, by the same means which actuates the alternating member 2, to which end, I provide the hasp with a releaser 54 (Figs. 2, 3 and 4) pivoted at 55 to the hasp and bearing a lifting stud 56 projecting through a slot 57 formed in the hasp. A spring 58 contacts the lifting stud 56 to 20 yieldingly hold the latter at the upper end of the slot 57 in the hasp 50. The free end of the releaser 54 projects in advance of the hasp and carries an inclined lip 54^m lying in the arcuate path of a trip stud 59 projecting from the adjacent actuating arm 1'.

As shown in Fig. 2, the trip stud lies some distance behind the inclined lip 54^m when the machine is in its position of rest. 30 The main drive shaft 200, on its forward stroke, swings the actuating arms 1, 1' idly forward, the trip stud 59 contacting the rear face of the inclined lip 54^m and depressing the releaser 54 idly against the tension of 35 the spring 58, which restores the releaser to its normal elevated position after the trip stud clears the lip.

The trip stud 59, on its return stroke, encounters the outer overhanging face of the 40 lip 54^m prior to the contact of either actuating arm 1, 1' with the effective tappet 5 or 5', and as the stud cannot depress the releaser as on the forward stroke, it forces the releaser 54 upwardly, and the lifting stud 56 lying at the upper end of the slot 57 in the hasp 50, raises the hasp to disengage it from the keeper 7. The overhanging lip is of sufficient length to maintain contact with the trip stud 59 until one of the actuating arms 1, 1' has had time to contact the effective tappet 5, or 5' and swing the alternating member 2 so as to displace the keeper 7 relatively to the aperture 53 which was fitted thereover, after which the trip stud 59 escapes the releaser and permits the 55 spring 58 to press the flange 54^m of the releaser down upon the keeper 7 in readiness to slip over the keeper when the latter reaches the opposite end of its travel, and 60 lock the parts in place.

As hitherto mentioned, it is desirable that the line spacing mechanism be disabled or silenced on alternate operations of the machine to enable two amounts to be printed 65 on the same line, and I have contrived an

extremely simple, and inexpensive means to effect this result.

In so doing, I have placed the line space disabling mechanism under the control of the communicating lever 19, 20 and I also 70 arrange to actuate the line space disabling mechanism by such lever.

At least two novel advantages obtain from this arrangement, one being to relieve the operator of the necessity of remembering to depress or release any manually-operable member to set the line space disabling mechanism for operation or to render the disabling mechanism ineffective, another advantage being that the carriage can 80 be shuttled and the line space disabling mechanism can be rendered alternately effective and ineffective, if it is desired to print two columns of amounts, all of which are to be accumulated.

85 A lever 60 (best shown in Fig. 7) fast on a shaft 61 journaled in ears 62 projecting rearwardly from the hanger 23, carries a check member or roll 63 shiftable into and out of the path of advance of the universal 90 line space bail 2002. One arm of a bell crank lever 64 engages the inner end of the lever 60 and a spring 65 (Fig. 6) connected to the bell crank lever 64, normally holds the latter at one end of its throw against a 95 stop 66, (Fig. 8) to retain the check member 63 in idle position.

To effect the operation of the line space disabling mechanism, I employ the spring-pressed operating finger 40, whose outer end 100 bears against the inner face of the adjustable crank 20 of the communicating lever 19, 20, to hold the crank 20 and its separable coupling member 28, disconnected from and out of the path of travel of the coöperating 105 member 29 on the carriage.

When the operator desires to list amounts alternately in two columns, he will swing the adjustable crank 20 against the tension of the spring-pressed thrust finger 40 until 110 the members of the separable coupling 28, 29 are brought in juxtaposition and then turn the rotatable member 28 until it fits over the rib 34 on the member 29 secured to the carriage. The turn button 37 will have 115 passed through the slot 38 in the adjustable crank 20 and the operator will turn the button to hold the crank where adjusted.

Furthermore, the crank 20, in swinging to its effective position, will force the operating finger 40 inwardly against the tension of the spring 39 and project the inner end of the finger into the plane of movement of the bell crank 64, as shown in Fig. 9. In case the connection between the communicating lever 19, 20 and the carriage, is effected when the lever is in the position shown in Fig. 8, the operating finger 40 will be at that end of its travel farthest removed from the bell crank lever 64 and the spring 130

65 functioning through the bell crank 64 will hold the check member 63 in idle position, as illustrated in the same figure and in Figs. 2, 3 and 9.

5 The carriage, in these figures, is positioned to the left, to locate the right hand column at the printing point, in which position, it remains during the succeeding forward stroke of the main drive shaft, but 10 upon the return stroke of the shaft, the actuating arm 1 contacts its tappet 5 to rock the alternating member 2 and swing the communicating lever 19, 20 to the opposite limit of its travel. The lever shifts the carriage 15 to the right to bring the left hand column to the printing point, and the operating finger 40 carried by the lever, impinges against the depending arm of the bell crank lever 64 to shift the bell crank and rock the line 20 space disabling lever 60 to bring the check member 63 into the path of the universal line space bail 2002, as shown in Fig. 6. Upon the next forward stroke of the main 25 drive shaft, the thrust bar 2024 withdraws from in front of the bail 2002 and the spring 2486 (Fig. 8) tends to advance the bail, but the check member 63 prevents such advance and retains the bail substantially 30 in its retired position until the thrust bar 2024, on the return stroke, resumes its effective position.

As the communicating lever 19, 20 swings back to its position shown in Fig. 8, it carries with it the operating finger 40, thereby 35 releasing the bell crank 64 to the action of its spring 65, which thereupon returns the check member to idle position.

In case the connection between the communicating lever 19, 20 and the carriage is effected when the lever is in the position shown in Fig. 6, the inner end of the operating finger 40 will strike the depending arm of the bell crank 64 which at that time will be held by its spring 65 in the path of the 45 finger with the check member 63 in idle position. To provide for such a contingency, the depending arm of the bell crank lever 64 is preferably made of resilient material to yield inwardly when the operating finger 50 presses thereagainst. The operator will then take an idle stroke which will shift the communicating lever to the opposite limit of its throw, the operating finger traveling therewith and releasing the depending arm of the 55 bell crank lever which restores to position to be contacted by the operating finger 40 on the next operation of the machine.

In classes of work wherein it is desired to print a designating number or other indicia, and an amount, on the same line but in different columns, the designating number and the amount being printed in successive operations of the machine, it is customary to render the accumulating mech-

anism ineffective when printing the designating indicia.

I have devised an extremely simple and easily operated means to automatically disable the accumulating mechanism on alternate operations of the machine, and one 70 which because of the few parts employed, is not readily liable to get out of order. And in so doing, I have contrived to utilize the usual manually-operable non-add mechanism of the Wales machine, with such 75 changes as will enable it to be automatically operated.

In the Wales machine, as shown in U. S. patent to McFarland, 1,024,013, above mentioned, a cross shaft 404 (Figs. 1 and 2) 80 journaled in the opposite side frames 967, carries hooks or restraining members 417 adapted to swing beneath the projecting ends of the counter-supporting axle 409 when the latter is in its normally elevated 85 position, to prevent the axle and the counters 490 from engaging the racks 310. Normally the restraining members 417 lie in idle position (Figs. 1 and 2) out of the path of the counter-supporting axle. 90

Depression of a key directly pivoted to a rearwardly extending arm fast on the rock shaft supporting the restraining hooks, turns the shaft to swing the hooks to effective position. And by locking the key 95 in depressed position, successive amounts might be printed without being accumulated.

In the present invention, however, in order to permit the hooks or restraining 100 members 417 to be automatically displaced while the key 424 remains in depressed position, I provide a spring link 67 (Fig. 2) to connect the key 424 with an arm 68 fast on the shaft 404. Depressing the key tensions the spring to rock the restraining 105 members 417 to effective position.

A notch 424^m on the keystem engages the edge of the slot in the usual casing inclosing the machine, indicated at 1065, through 110 which the key projects, to retain the non-add mechanism effective. Releasing the key 424 relieves the tension of the spring link 67 to enable a spring 481 connected by a link 69 with one of the restraining hooks 115 417 to retire the restraining hooks to idle position.

I contrive to render the non-add mechanism automatically effective and ineffective alternately on successive operations of the 120 machine, to relieve the operator of the necessity of remembering to manually depress and release the key 424, as follows:

Locking the key 424 in depressed position, maintains the spring 67 under tension 125 to overcome the restoring spring 481 and hold the restraining members 417 effective.

To restore the restraining members to

ineffective position, notwithstanding the continued depression of the non-add key 424, and then free the members to the influence of the spring 67, on alternate operations of the machine, I connect the link 69 with the upper arm of a lever 70 pivoted intermediate its ends at 71, the remaining arm of the lever being connected to a draft shackle 72 (Fig. 3) having a slot 73 formed therein to embrace a headed stud 74 projecting from and forming an extension of the pivot 6 of the tappet 5.

The slot 73 in the shackle 72 is of such length that when the non-add mechanism is in its idle position, the stud 74, carried by the alternating member 2 idly traverses the slot without actuating the shackle.

Depressing the key 424 to swing the restraining members 417 to effective position, causes one of the restraining members, to advance the link 69 and thereby rock the lever 70 against the tension of restoring spring 481 to shift the shackle 72 so as to bring one end wall of the slot 73 therein, into the path of the actuating stud 6. In the form shown, the shackle 72 shifts rearwardly when the key 424 is depressed, to bring the forward end of the slot into the path of the actuating stud, providing the alternating member 2 with its stud 6 is not already in the position shown in Fig. 3.

In such position, the stud 6 prevents the shackle 72 from shifting backwardly, and though the key 424 may be locked in depressed position, the counter-restraining members 417 cannot rock to effective position, owing to their connection through the link 69 and lever 70, with the shackle.

This arrangement prevents the non-add mechanism from disabling the accumulating mechanism when the carriage has positioned the column for accumulated amounts at the printing line.

However, the spring 67 will remain under tension due to the depression of the non-add key 424, and as soon as the actuating arm 1 shifts the alternating member 2 in a counter-clockwise direction, and the accumulator axle 400 returns to elevated position, the restraining hooks 417 will snap thereunder, and the shackle 72 will retract toward the rear of the machine, to bring the forward end wall of its slot 73 into the path of the stud 6.

Upon the next return stroke of the main drive shaft, during which, the actuating arm 1 contacts the active tappet 5' to swing the alternating member 2 in a clockwise direction to drive the carriage to the left and thereby position the right hand column at the printing point, the actuating stud 6 travels forwardly along the slot 73 in the shackle 72 until it finally strikes the front end of the slot and draws the shackle for-

wardly to rock the upper arm of the lever 65 70 rearwardly. The lever through the link 69 swings the restraining members 417 to idle position, further tensioning the drive spring 67. The parts remain in these positions, and hence, the amount next set up 70 on the keyboard, will be printed in the right hand column and will be accumulated on the counters which will have dropped into engagement with the racks 310 at the end of the forward stroke of the main drive 75 shaft.

The main drive shaft, on its return stroke, will again rock the alternating member 2 in counter-clockwise direction, during which the actuating stud 6 retreats from the forward end of the slot 73 in the shackle 72, freeing the latter and the lever 70 to the action of the tensioned drive spring 67 which swings the arm 68 downwardly to thrust the restraining hooks 417 forwardly to effective 85 position.

The hooks cannot, at this time, take under the counter-supporting axle 400 as the latter is in lowered position, and consequently 90 beneath and lock the counters in idle position, as soon as the counter-disengaging props 319 return the axle to its normal elevated position.

The alternating member 2 operated directly from the main drive shaft, thus alternately permits and prevents the non-add mechanism from functioning on successive operations of the machine.

Obviously, it is desirable to prevent depression of the total and sub-total keys 327 and 327^b when the carriage is at its right hand limit of reciprocation with the left hand column for unaccumulated designating numbers at the printing point, as a totaling 100 operation at that time would print the total 105 of the accumulated amounts beneath the column of designating indicia.

This result is readily effected by the use of the mechanism disclosed in U. S. patent 110 to McFarland 880,159, February 25, 1908. Referring to Fig. 1, it will be remembered that depression of either key 327 or 327^b rocks the set lever 317^b to advance the slide 320 connected to the set lever. Obviously, 115 if the slide is locked against advancing, the keys cannot be depressed.

Such locking means includes a latch 619 journaled intermediate its ends on a cross shaft 603 mounted in the side frames. An 120 angular slot 619^m formed in the forward arm of the latch 619 embraces a pin 254^b projecting from the slide 320. Normally, the pin 254^b lies in the angle of the slot, and upon depression of either key 327 or 327^b, the slide 125 320 on its advance, causes the pin to travel along that branch of the slot 619^m corresponding with the path of the slide.

The rear arm of the latch 619 lies in the path of a stud 457 conveniently carried on one of the restraining members 417. As such member shifts to effective position, the 5 stud 457 contacts the rear arm of the latch 619 to rock the latter and fit that branch of the slot 619^a which lies transversely to the path of the slide 320, over the pin 254^b, thereby preventing the advance of the slide and 10 locking the total and sub-total keys 327 and 327^b, respectively, against depression.

To enable the operator to disable the alternating member 2, whereby to prevent the operation and consequent unnecessary 15 wear of the member, when ordinary work is to be performed on the machine, I provide a bolt or stop member 75 (Figs. 3 and 5) slidably mounted in the base 968. A spring 76 is adapted to rest in either of two notches 77, 20 78, spaced apart along the bolt, retains the latter in its outer ineffective position, or at its inner effective position wherein it projects into the path, and just in front of, the tappet 5 when the latter is in its active position 25 at the end of the counter-clockwise stroke of the alternating member. It will be remembered that the tappets 5 or 5' remain in their active positions during the return stroke of the main drive shaft and are 30 held by the actuating arms 1 or 1' against rocking to idle position until the arms on the succeeding forward stroke, retract from the active tappet to enable the tensioned spring 13 or 14 to switch the tappets.

35 Should the operator adjust the bolt 75 to its effective position while the alternating member 2 is at the end of its clockwise stroke, at which time the tappet 5 is idle (full lines Fig. 3) no harm will result, as the tappet 5 40 on the succeeding counter-clockwise stroke, will contact and cam the bolt outwardly to its ineffective position, after which and before commencing the next forward stroke of the main drive shaft, the operator will 45 place the bolt in effective position to lock the tappet 5 in the dotted line position shown in Fig. 3, to hold the opposite tappet 5' in its idle position against the influence of the spring 13, which is tensioned at that time.

50 The operator, when setting the machine for ordinary work, will manually release the non-add key 424, to enable the spring 481 to restore the restraining members 417 to idle position. He will also withdraw the 55 spring-pressed pin 42 (Fig. 8) to allow the spring 481^a to return the tabulating bar stops 2018^b to effective position relatively to the abutment 2091^a, and will rotate the turn button 37 to release the adjustable 60 crank 20 to the action of the tensioned spring 39, which, through the operating finger 40, disconnects the couplings 28, 29 and swings the crank rearwardly, thereby enabling the operating finger to retire from 65 its effective position relatively to the line

space disabling bell crank 64, to permit line spacing on successive operations of the machine.

Changes may be made in the form and arrangement of the several parts set forth, 70 certain of which may be used alone, as heretofore explained, without departing from the spirit and scope of my invention.

What I claim as new, is:—

1. In a calculating machine, the combination with a driving means; and a shiftable paper carriage; of an actuator operable by the driving means; a rocker; a tappet mounted thereon to shift into and out of the path of the actuator; means controlled 80 by the rocker to automatically swing the tappet alternately into and out of the path of the actuator; and means driven by the rocker to shift the carriage in one direction upon the contact of the actuator with its 85 tappet.

2. In a calculating machine, the combination with a driving means; and a shiftable paper carriage; of actuators operable by the driving means; a rocker fulcrumed intermediate its ends; tappets mounted on the rocker, on opposite sides of its fulcrum, to shift into and out of the path of the respective actuators; means controlled by the rocker, to automatically shift either one of 90 the tappets into, and the remaining tappet out of, the path of its actuator, to enable the actuators to swing the rocker in first one direction and then the other, alternately, on successive operations of the driving means; and means to connect the rocker with the carriage, to shift the latter back and forth.

3. In a calculating machine, the combination with a driving means; and a shiftable 105 paper carriage; of actuators operable by the driving means; an oscillatory rocker; tappets pivotally mounted on the rocker; a switch mechanism to automatically shift the tappets individually and alternately 110 into and out of the paths of their respective actuators; and means driven by the rocker, to shift the carriage back and forth.

4. In a calculating machine, the combination with a driving means; and a shiftable paper carriage; of actuators operable by the driving means; a rocker fulcrumed intermediate its ends; tappets mounted on the rocker, on opposite sides of its fulcrum, to shift into and out of the path of the respective actuators; means controlled by the rocker, to automatically shift either one of the tappets into, and the remaining tappet out of, the path of its actuator, to enable the actuators to swing the rocker in first 120 one direction and then the other, alternately, on successive operations of the driving means; means driven by the rocker to shift the carriage back and forth; and releasable means to arrest and lock the rocker and car- 125 130

riage in at least one of its operated positions.

5. In a calculating machine, the combination with a driving means; and a shiftable paper carriage; of actuators operated from the driving means and traversing a fixed path; a fulcrumed rocker; tappets pivotally connected to the rocker, on opposite sides of the fulcrum thereof; a switch mechanism controlled by the rocker, to shift the tappets singly and alternately into and out of the path of their actuators, respectively; and means driven by the rocker to shift the carriage alternately in opposite directions, on successive operations of the driving means.

6. In a calculating machine, the combination with a driving means; and a shiftable paper carriage; of actuating arms operated by the driving means; a rocker fulcrumed intermediate its ends; means to connect the rocker and paper carriage; tappets mounted on the opposite arms of the rocker to constitute extensions thereof, and movable relatively thereto, into and out of the paths of their respective actuating arms; and means controlled by the rocker to switch one of the tappets into, and the remaining tappet out of, the paths of travel of their respective actuating arms, alternately, on successive operations of the driving means.

7. In a calculating machine, the combination with a driving means; and a shiftable paper carriage; of actuating arms operated by the driving means; a rocker fulcrumed intermediate its ends; means to connect the rocker and paper carriage; tappets mounted on the opposite arms of the rocker to constitute extensions thereof, and movable relatively thereto, into and out of the paths of their respective actuating arms; means controlled by the rocker to switch one of the tappets into, and the remaining tappet out of, the paths of travel of their respective actuating arms, alternately, on successive operations of the driving means; and means to lock the rocker out of operation at one end of its travel.

8. In a calculating machine, the combination with a driving means; and a shiftable paper carriage; of actuating means operated from the driving means; a fulcrumed rocker; tappets pivoted to the rocker on opposite sides of its fulcrum; a switch mechanism controlled by the rocker to shift the tappets alternately into and out of the path of the actuating means; and a releasable connection between the rocker and carriage to shift the latter back and forth.

60 9. In a calculating machine, the combination with a driving means; and a shiftable paper carriage; of actuating means operated from the driving means; an alternating member; tappets shiftably connected to the alternating member, for adjustment into and

out of the path of the actuating mechanism; a switch mechanism controlled by the alternating member to shift the tappets singly and alternately into and out of the path of the actuating mechanism; and means to connect the alternating member and the carriage, to shift the latter back and forth.

10. In a calculating machine, the combination with a driving means; and a shiftable paper carriage; of actuating means operated from the driving means; an alternating member; tappets shiftably connected to the alternating member, for adjustment into and out of the path of the actuating mechanism; an oscillatory switch lever, one arm of which is pivotally connected with the alternating member for operation thereby; a link to connect the tappets; opposed springs, whose inner ends are connected to the remaining arm of the switch lever, the outer ends of the springs being connected to the link near its opposite ends, respectively, whereby as the switch lever swings to one or the other of its positions, it tensions either one of the springs and relaxes the remaining spring to automatically shift one or the other tappet into the path of the actuating means, and withdraw the remaining tappet to idle position; and means to connect the alternating member and the carriage to shuttle the latter.

11. In a calculating machine, the combination with a driving means; and a shiftable paper carriage; of actuating arms operated by the driving means; a rocker fulcrumed intermediate its ends; means to connect the rocker and paper carriage; tappets mounted on the opposite arms of the rocker to constitute extensions thereof, and movable relatively thereto, into and out of the paths of their respective actuating arms; a link to connect the tappets; opposed springs, whose outer ends are respectively connected to the link; a switch lever to which the inner ends of the springs are connected, the rocker adapted to control the switch lever to swing it alternately to one or the other limit of its throw, to tension one or the other of the springs and relax the remaining spring, whereby to shift the link in one direction or the other, to thereby move either one of the tappets into the path of its actuating arm, and to coincidentally move the remaining tappet out of the path of its actuating arm.

12. In a calculating machine, the combination with a driving means; and a shiftable paper carriage; of actuating arms operated by the driving means; a rocker fulcrumed intermediate its ends; means to connect the rocker and paper carriage; tappets mounted on the opposite arms of the rocker to constitute extensions thereof, and movable relatively thereto, into and out of the paths of their respective actuating arms; means controlled by the rocker to switch one

of the tappets into, and the remaining tappet out of, the paths of travel of their respective actuating arms, alternately, on successive operations of the driving means, the 5 actuating arms, when at rest, adapted to retain the active tappet in effective position, against the influence of the rocker-controlled switch means; and a lock to engage the active tappet when in effective position at 10 the end of its travel, to hold the rocker idle.

13. In a calculating machine, the combination with a driving means; and a shiftable paper carriage; of actuating arms operated by the driving means; a rocker fulcrumed intermediate its ends; means to connect the rocker and paper carriage; tappets mounted on the opposite arms of the rocker to constitute extensions thereof, and movable relatively thereto, into and out of the 15 paths of their respective actuating arms; means controlled by the rocker to switch one of the tappets into, and the remaining tappet out of, the paths of travel of their respective actuating arms, alternately, on successive 20 operations of the driving means; and adjustable means to arrest the alternating member in one limit of its travel against operation.

14. In a calculating machine, the combination with a driving means; and a shiftable paper carriage; of actuating means operated from the driving means; an alternating member; tappets shiftably connected to the alternating member, for adjustment into 25 and out of the path of the actuating mechanism; a switch mechanism controlled by the alternating member to shift the tappets singly and alternately into and out of the path of the actuating mechanism; means to 30 connect the alternating member and the carriage, to shift the latter back and forth; and means adjustable into and out of the path of one of the tappets to arrest the alternating member in one limit of its travel 35 against operation.

15. In a calculating machine, the combination with a driving means; and a shiftable paper carriage; of actuating means operated by the driving means; a substantially 40 T-shaped member fulcrumed intermediate the ends of its cross-piece; tappets pivoted intermediate their ends near the opposite ends of the cross-piece; stops lying in the paths of the inner arms of the tappets to 45 arrest the rotation of the latter in one direction, with the outer arms of the tappets extending beyond and forming continuations of the cross-piece, to lie in the paths of the actuating means; a switch lever fulcrumed intermediate its ends; one arm of the switch lever pivotally connected to the T-shaped member eccentrically of its fulcrum; a link to connect the inner arms of the tappets; oppositely extending springs 50 to connect the remaining arm of the switch

lever with the opposite ends of the link; and means to connect the stem of the T-shaped member and the carriage to shift the latter back and forth, coincidently with the operation of the T-shaped member by the 55 actuating means.

16. In a calculating machine, the combination with a driving means; and a shiftable paper carriage; of actuating means operated by the driving means; a rocker fulcrumed intermediate its ends; extensions shiftably mounted near the respective opposite ends of the rocker; means controlled by the rocker to shift one or the other of the extensions into, and the remaining extension 60 out of, the path of the actuating means, alternately; and means to connect the rocker and the carriage, to shift the latter back and forth.

17. In a calculating machine, the combination with a driving means; and a shiftable paper carriage; of an alternating member connected with the paper carriage, and pivoted intermediate its ends, the alternating member adapted to lie at one or another of its limits of travel with one or another of its arms advanced; the driving means operating independently of the alternating member, and adapted to contact the advanced arm of the alternating member, 65 to rock the member to its opposite limit of travel and thereby interpose the arm on the opposite side of its pivot, into the path of the driving means, and to shift the paper carriage; and a disabling device to prevent 70 the contact between the driving means and the alternating member.

18. In a calculating machine, the combination with a driving means; and a shiftable paper carriage; of an alternating member connected with the paper carriage; means operated by the driving means to contact the alternating member at its opposite ends alternately on successive operations of the driving means, to shift the alternating member and shuttle the paper carriage back and forth; and means to lock the alternating member at one end of its travel to prevent its operation.

19. In a calculating machine, the combination with a keyboard; calculating and printing mechanisms; driving means; and a paper carriage, shiftable relatively to the printing mechanism to bring one or another column to printing position; of an oscillatory rocker; tappets pivotally mounted at opposite ends of the rocker; stops to arrest the tappets in one direction; actuators to contact the tappets, and swing the rocker alternately, in opposite directions; a switch mechanism adapted to connect the tappets to shift them alternately into and out of the paths of their respective actuators; manually-operable means to disable the rocker; and means to connect the rocker 120 125 130 135

and carriage, to shift the carriage back and forth.

20. In a calculating machine, the combination with a driving means; and a shiftable paper carriage; of actuating means operable by the driving means; a rocker oscillating in a plane at an angle to the planes of operation of the actuating means, the actuating means adapted to clear the ends of the rocker; extensions shiftably mounted on the rocker; means, controlled by the rocker, to switch one or the other of the extensions into, and the remaining extension out of, the path of the actuating means, alternately; and means to connect the rocker and paper carriage.

21. In a calculating machine, the combination with a shiftable paper carriage; of a driving means; a rocker driven thereby; 20 separate members shiftably mounted on the rocker; a switch mechanism to automatically move one of the shiftable members into, and the other out of, the path of the driving means alternately; and means actuated by the rocker to shift the carriage back and forth.

22. In a calculating machine, the combination with a driving means; and a shiftable carriage; of means to shift the carriage in opposite directions on alternate operations of the driving means; means to releasably detain the last named means in at least one of its adjusted positions, to hold the carriage against accidental displacement, and adapted for release by the driving means, prior to the actuation of the carriage-shifting means by the driving means.

23. In a calculating machine, the combination with a driving means; and a shiftable carriage; of an alternating mechanism shiftable in opposite directions on successive operations of the driving means; means to connect the alternating member and carriage to shift the latter back and forth; and 45 means controlled by the driving means to releasably lock the alternating mechanism and carriage in one or the other of its positions.

24. In a calculating machine, the combination with a driving means; and a shiftable paper carriage; of an alternating mechanism shiftable in opposite directions alternately on successive operations of the driving means; means to connect the alternating mechanism and the carriage, to shift the latter back and forth; means to releasably lock the alternating mechanism and carriage in their extreme positions; and means controlled by the driving means to disable the lock prior to the actuation of the alternating mechanism.

25. In a calculating machine, the combination with a driving means; and a shiftable paper carriage; of an alternating mechanism shiftable in opposite directions alter-

nately on successive operations of the driving means; means to connect the alternating mechanism and the carriage, to shift the latter back and forth; a keeper fixed to travel with the alternating mechanism; a 70 hasp having a pair of apertures spaced apart a distance equal to the extreme travel of the keeper, and adapted to fit over the keeper; and means controlled by the driving means to disengage the hasp from the keeper 75 prior to the actuation of the alternating mechanism.

26. In a calculating machine, the combination with a driving means; and a shiftable paper carriage; of an alternating mechanism shiftable in opposite direction alternately on successive operations of the driving means; means to connect the alternating mechanism and the carriage, to shift the latter back and forth; a keeper fixed to travel 80 with the alternating mechanism; a hasp having a pair of apertures spaced apart from each other a distance equal to the extreme limits of travel of the keeper; means normally tending to press the hasp toward 85 the keeper to fit one or the other of the apertures over the keeper, to hold the alternating member and carriage in either adjusted position; and releasing means controlled by the driving means to disengage the hasp from 90 the keeper prior to the actuation of the alternating mechanism.

27. In a calculating machine, the combination with a driving means; and a shiftable paper carriage; of an alternating mechanism shiftable in opposite directions alternately on successive operations of the driving means; means to connect the alternating mechanism and the carriage, to shift the latter back and forth; a keeper fixed to travel 100 with the alternating mechanism; a hasp having a pair of apertures spaced apart from each other a distance equal to the extreme limits of travel of the keeper, to engage and fit over the keeper when the latter is at either 105 limit of its travel, and hold the alternating mechanism and carriage where shifted; a releaser connected with the hasp for limited relative movement thereto; means to restore the releaser to, and yieldingly hold it at, one 110 limit of its movement; an inclined lip on the releaser; and a wiper operated by the driving means to contact the lip and idly operate the releaser relatively to the hasp, when traveling in one direction, and to effectively 115 operate the releaser to disengage the hasp from its keeper, when traveling in the opposite direction.

28. In a calculating machine, the combination with a main drive shaft; and a 125 shiftable paper carriage; of an alternating mechanism shiftable in opposite directions, alternately, by the main drive shaft on successive operations; means to connect the alternating mechanism and carriage to shift 130

the latter back and forth; a keeper fixed to travel with the alternating mechanism; a hasp having a pair of apertures, terminating in relatively convergent guide slots, and spaced apart a distance equal to the travel of the keeper, the apertures adapted to fit over the keeper to lock the alternating mechanism at either end of its stroke; and means controlled by the main drive shaft, to disengage the hasp from the keeper prior to the actuation of the alternating mechanism.

29. In a calculating machine, the combination with a driving means; and a shiftable paper carriage; of an alternating member shiftable alternately in opposite directions, on successive operations of the driving means; a crank lever, one crank of which is connected with the alternating member, the remaining crank being hinged; and a separable slide connection between the hinged crank and the carriage.

30. In a calculating machine, the combination with a driving means; and a shiftable paper carriage; of an alternating member shiftable alternately in opposite directions, on successive operations of the driving means; a crank lever, one crank of which is connected with the alternating member, the remaining crank being hinged; a slotted coupling member journaled in the hinged crank; a ribbed coupling member adjustably secured to the carriage, the slotted coupling member having a sliding fit on the ribbed coupling member; and means to secure the hinged crank in position to hold the coupling members together.

31. In a calculating machine, the combination with a driving means; and a shiftable paper carriage; of an alternating member actuated by the driving means in alternate opposite directions in one plane of movement, on successive operations of the driving means; an oscillatory crank lever shiftable in a plane of movement at an angle to the plane of movement of the alternating member; a fork journaled in the alternating member; a wrist pin on the oscillatory lever embraced by the fork; and a separable slide coupling to connect the lever and carriage, one member of the coupling being journaled for rotary movement.

32. In a calculating machine, the combination with a driving means; and a shiftable paper carriage; of an alternating member actuated by the driving means in alternate opposite directions, on successive operations of the driving means; an oscillatory crank lever driven by the alternating member, the lever including a crank hinged to swing in a plane at an angle to the oscillatory travel of the lever, and having an opening formed therein; a post on the crank lever relatively to which the hinged crank swings; a turn button on the post adapted to project

through and overlie the walls of the opening in the hinged crank, to lock the latter in effective position; and a slide coupling to releasably connect the hinged crank and the paper carriage.

33. In a calculating machine, the combination with a shiftable paper carriage; an oscillatory lever; and means to oscillate the lever; of a separable coupling to connect the lever and the paper carriage, including a member journaled in the lever and having a slot; a co-acting member secured to the carriage, and having a rib over which the slotted member fits, the co-acting members adapted to slide relatively to each other, as the lever oscillates in driving the carriage in one direction or the other; and means to releasably maintain an operative connection between the coupling members.

34. In a calculating machine, the combination with a driving means; a shiftable paper carriage; and line space mechanism; of an alternating mechanism actuated in opposite directions on successive operations of the driving means; a releasable connection between the alternating mechanism and the carriage; and means controlled by the releasable connection, to disable the line space mechanism.

35. In a calculating machine, the combination with a driving means; a shiftable paper carriage; and line space mechanism; of an alternating mechanism actuated in opposite directions on successive operations of the driving means; a releasable connection between the alternating mechanism and the carriage; normally idle means to disable the line space mechanism; and means controlled by the releasable connection to render the line space disabling means effective on alternate operations of the driving means.

36. In a calculating machine, the combination with a driving means; a shiftable paper carriage; and line space mechanism; of an alternating mechanism actuated in opposite directions on successive operations of the driving means; a releasable connection between the alternating mechanism and the carriage; means to disable the line space mechanism; a normally idle operating member to shift the line space disabling means to effective position, said operating member being located in active position as an incident to effecting the union between the releasable connection and the carriage, and adapted to actuate the line space disabling means on alternate operations of the driving means.

37. In a calculating machine, the combination with a main drive shaft; a shiftable paper carriage; and line space mechanism normally operable at each operation of the main drive shaft; of means driven by the main drive shaft to shift the carriage alternately in opposite directions, including a dis-

- placeable member releasably connected with the carriage to shift back and forth therewith; means to disable the line spacing mechanism; and an operating member for the line space disabling means, controlled by the displaceable member to be adjusted thereby into and out of effective position relatively to the line space disabling means, and driven by the carriage-shifting means to automatically actuate the line space disabling means to effective position only on alternate operations of the main drive shaft.
38. In a calculating machine, the combination with a driving means; a shiftable paper carriage; and line space mechanism; of a train of connections, including a displaceable member, actuated by the driving means, to shift the carriage alternately in opposite directions; means to disable the line space mechanism; an operating member therefor, shiftable under the control of the displaceable member, into and out of its active position wherein it can operate the line space disabling means, and actuated through said train of connections to render the line space disabling means effective and ineffective on alternate operations of the driving means, while the displaceable member remains in effective position to shift the carriage.
39. In a calculating machine, the combination with a driving means; a shiftable paper carriage; and line space mechanism; of an alternating mechanism driven in opposite directions alternately, by the driving means on successive operations; a train of connections between the alternating mechanism and the carriage, to enable the alternating mechanism to shift the carriage back and forth, the train of connections including a displaceable crank, which when displaced, interrupts the transmission of power from the driving means to the carriage; means to lock the crank in effective position; means to disable the line space mechanism; an operating member mounted in the train of connections, and adjustable into and out of active position under control of the displaceable crank, as an incident to the adjustment of the displaceable crank into and out of effective position, the operating member adapted to alternately contact and release the line space disabling mechanism to successively prevent and permit the operation of the line space mechanism.
40. In a calculating machine, the combination with a driving means; a shiftable paper carriage; and line space mechanism; of an alternating mechanism driven in opposite directions alternately, by the driving means on successive operations; a train of connections between the alternating mechanism and the carriage, to enable the alternating mechanism to shift the carriage back and forth, the train of connections including a hinged crank connectible with and disconnectible from the carriage; means to lock the crank in connected position; means to disable the line space mechanism; an operating finger controlled by the hinged crank and slidably mounted in the train of connections, the finger being adjustable into and out of effective position relatively to the line space disabling means, under control of the crank; and a spring to withdraw the operating finger to its ineffective position, and to yieldingly hold the hinged crank disconnected from the carriage.
41. In a calculating machine, the combination with a driving means; a shiftable paper carriage; and a line space mechanism; of an alternating member shifted by the driving means in opposite directions, on successive operations of the driving means; an oscillatory crank lever, one crank of which is connected for movement relatively to the other crank; means to connect the lever to the alternating member, and to the carriage, respectively; means to disable the line space mechanism, including a check member; an elbow lever connected thereto, to shift the check member from one to another of its positions; and an operating finger adjustable into and out of active position, under control of the relatively movable crank of the oscillatory lever, and adapted, when in active position, to drive the elbow lever, as the oscillatory lever rocks in one direction.
42. In a calculating machine, the combination with a driving means; a shiftable paper carriage; and a line space mechanism; of an alternating member shifted by the driving means in opposite directions, on successive operations of the driving means; an oscillatory crank lever, one crank of which is connected for movement relatively to the other crank; means to connect the lever to the alternating member, and to the carriage, respectively; means to disable the line space mechanism; and an operating finger adjustable into and out of active position, under control of the relatively movable crank, the operating finger, when in active position, adapted to actuate the line space disabling means as the lever rocks in one direction.
43. In a calculating machine, the combination with a main drive shaft; a shiftable paper carriage; a set of counters, and a set of drive members therefor, adapted for relative engagement and disengagement; and non-add mechanism to prevent the engagement of the counters and drive members of a key having a flexible connection with the non-add mechanism, to shift the latter to effective position; and means controlled from the main drive shaft to return the non-add mechanism to idle position on alternate

operations of the shaft, against the influence of the flexible connection to retain the non-add mechanism effective.

44. In a calculating machine, the combination with a main drive shaft; a shiftable paper carriage; a set of counters, and a set of drive members therefor, adapted for relative engagement and disengagement; and non-add mechanism to prevent the engagement 5 of the counters and drive members; of a key having a flexible connection with the non-add mechanism, to shift the latter to effective position; an alternating member actuated in opposite directions on alternate operations of the main drive shaft; and a normally idle connecting device set by the key to enable the alternating member to return the non-add mechanism to idle position on alternate operations, against the influence of 10 the flexible connection to retain the non-add mechanism effective.

45. In a calculating machine, the combination with a main drive shaft; a shiftable paper carriage; a set of counters, and a set of drive members therefor, adapted for relative engagement and disengagement; and non-add mechanism to prevent the engagement 15 of the counters and drive members; of a key having a flexible connection with the non-add mechanism to shift the latter to effective position; means controlled from the main drive shaft to return the non-add mechanism to idle position on alternate operations of the shaft, against the influence 20 of the flexible connection to retain the non-add mechanism effective; and a lock to render the return mechanism idle.

46. In a calculating machine, the combination with a main drive shaft; a shiftable paper carriage; a set of counters, and a set of drive members therefor, adapted for relative engagement and disengagement; and non-add mechanism to prevent the engagement 25 of the counters and drive members; of a key having a flexible connection with the non-add mechanism to shift the latter to effective position; an alternating member actuated in opposite directions on alternate operations of the main drive shaft; and a link having a lost motion connection with the alternating member and connected 30 with the non-add mechanism, the link adapted to be adjusted by the key to enable the alternating member to return the non-add mechanism to idle position on alternate operations against the influence of the flexible connection to retain the non-add mechanism effective.

47. In a calculating machine, the combination with a main drive shaft; a shiftable paper carriage; a set of counters, and a set of drive members therefor, adapted for relative engagement and disengagement; and non-add mechanism to prevent the engagement 35 of the counters and drive members; of a key having a flexible connection with the non-add mechanism to shift the latter to effective position; means controlled from the main drive shaft to return the non-add mechanism to idle position on alternate operations of the shaft, against the influence 40 of the flexible connection to retain the non-add mechanism effective; and a lock to render the return mechanism idle.

AMBROSIUS BRIECHLE
